GAME BOARD

Olivia Stickley, 9 Leisurely Lane, Bellport, N.Y.

Filed Oct. 8, 1963, Ser. No. 76,907

Term of patent 14 years

(Cl. D34—5)

The figure is a plan view of a game board, showing my new design.

The dominant features of my design reside in the portions shown in full lines. The board on which the design is imprinted or embossed is of conventional thickness.

I claim:

The ornamental design for a game board, substantially as shown and described.
